OTTO BAUERLE,

UNITED STATES PATENT OFFICE.

OTTO BAUERLE, OF SACRAMENTO, CALIFORNIA.

COALING DEVICE.

1,090,012.

Specification of Letters Patent. Patented Mar. 10, 1914.

Application filed July 9, 1913. Serial No. 778,141.

To all whom it may concern:

Be it known that I, Otto BAUERLE, a citizen of the United States, residing at Sacramento, in the county of Sacramento and State of California, have invented new and useful Improvements in Coaling Devices, of which the following is a specification.

The invention relates to a coaling device to provide for the automatic transference of coal from one steamer to another, the operation being automatic from the pick-up of the material in the bins of the one vessel and the discharge of said material into the bins of the other vessel.

The main object of the present invention is the provision of a coaling device for steamers involving a charging device and a delivery device, the former coöperating with the bins on the vessel from which coal is to be taken, and automatically picking up said material and delivering it to the delivery device, said delivery device being arranged to receive said material and automatically deliver it into the bins of the receiving vessel.

The invention in its preferred form of details will be described in the following specification, reference being had particularly to the accompanying drawings, in which:

Figure 1 is a plan illustrating the detail construction of the complete coaling machine. Fig. 2 is a side elevation of the machine. Fig. 3 is a transverse section on line 3—3 of Fig. 2. Fig. 4 is a transverse section on line 4—4 of Fig. 2. Fig. 5 is an enlarged end elevation of the charging buckets. Fig. 6 is a longitudinal central section of the same. Fig. 7 is an enlarged end elevation of one of the delivery buckets.

In carrying out the present improvement I provide a deck or other support 1 on which the coal to be delivered to the steamer is stored with what I term a charging apparatus and a delivery apparatus, the former designated generally by 2 being designed to take up the coal from the bins or pile and deliver it to the latter, designated by 3, the delivery apparatus in turn transporting the coal from the comparatively remote point and delivering it to the bins of the steamer to be coaled. The charging apparatus comprises an upright or standard 4 mounted upon the turn table 5 preferably formed of or provided with an annular gear rack 6 designed to be engaged by suitably operated

and controlled pinions 7 whereby the standard may be turned as desired. Pivotaly mounted upon the upper end of the standard 4 is what I term a boom 8 including a lower section inclined downwardly from its pivotal point on the standard and then projected to provide a section 9 which when the charging apparatus is in operative position will extend in parallelism with the coal storage floor or surface. The boom includes an upper section 10 which extends in a straight line between the terminals of the lower section. The boom comprises a suitable framework on which is supported the parallel tracks 11, the tracks being preferably supported from the sides so that their upper and lower surfaces are free to support the conveyers. The tracks follow the contour of the respective sections of the boom and are endless, constituting an endless trackway throughout the length of the boom. At appropriate points in the boom are arranged guide rollers 12, these rollers being preferably positioned intermediate the respective tracks, and an endless cable 13 is designed for travel over these rollers. The boom is connected to the standard 4 so that the adjacent end thereof, which constitutes the discharge end, extends beyond the standard in one direction, and supported within the boom at its point of connection with the standard is a motor 14 designed to impart continuous motion to the cable 13. Secured adjacent the standard 4 is an upright 15, and over an elevated pulley 16 on the same is arranged a cable 17, one terminal of which is connected to the boom 8 and the opposite terminal to the drum 18 arranged adjacent the bottom of the upright 15 and operative by any suitable power to actuate the cable 17 and thereby control the position of the boom 8 with respect to its elevation, the position of said boom with respect to its rotation being controlled through the gear teeth 6 and pinion 7, as previously described.

A series of charging buckets are adapted for coöperation with the boom 8. These buckets comprise metallic scoop bodies 19 closed at their rear ends and open at their forward ends, said forward ends being shaped to present a shovel edge 20. The buckets are mounted upon what may be termed upper and lower trucks, the former comprising wheels 21 arranged in pairs on each side of the bucket and adapted for travel upon relatively outer surfaces of the

respective tracks 11, the lower trucks comprising a single wheel 22 arranged on each side of the bucket and adapted for engagement with and travel upon the opposing 5 surface of the tracks. The trucks or axles supporting the lower wheels 22 are connected to the trucks supporting the upper wheels 21 by bars 23 normally operating under tension of springs 24 whereby the lower 10 wheels are at all times drawn toward the upper wheels, to permit a proper gripping of the opposing surface of the track, while providing for the necessary relative yielding in turning curves. The bucket is provided 15 with depending rigid frame 25 designed to be connected by any suitable manually controlled gripping element and a cable 13, so that in the operation of the cable the buckets travel throughout the length of the 20 boom 8, as will be plain from Figs. 1 and 2 of the drawings.

The delivery apparatus 3 comprises a boom 26, which includes an upright portion and a delivery portion 27 at approximately 25 right angles thereto. The boom 26 is mounted upon a standard 28 arranged for rotation through a gear rack 29 and suitably driven pinions 30, this boom also comprising a suitable framework supporting 30 spaced tracks 31 and an endless cable 32 driven by a motor 33 supported on the boom and traveling over pulleys 34 arranged between and beyond the plane of the tracks. A series of buckets 35 is arranged for co- 35 operation with the boom 26, comprising metallic bodies closed except at the top and forward ends, the latter being formed to provide spout like sections 36. The buckets 35 are supported upon the track 31 by upper and lower truck wheels 37, 38, engaging the opposite surfaces of the tracks, the lower truck wheels having spring connections 39 with upper trucks so as to maintain a sufficient pressure contact with the surfaces of 40 the tracks to properly guide the buckets. The buckets are provided with a frame 40 depending below the trucks and provided with any suitable form of creeper to engage the cable 32. The cable 41 is connected to 45 the boom 26 which passes from the pulley 42 on the upright 15 and to a suitably driven manually controlled drum 43 arranged at the lower end of the upright so that the boom may be elevated to any desired point. 50 Mounted upon the upright 15 is a chute 44, having its receiving end arranged to receive the material discharged from the charging buckets 19, and its delivery end arranged to

discharge such material into the delivery buckets 35. The feed through the chute is 60 by gravity. A swinging funnel 45 is carried by the free end of the boom 26, into which funnel the coal is delivered from the buckets 35, the funnel insuring delivery to the coal from the proper point on the receiving vessel.

In operation, the boom 8 is turned until above the coal pile from which the material is to be taken, and is then lowered until resting directly upon the coal. The cable 13 being operated the buckets 19 are caused to travel about the track, said buckets riding through the coal pile, and shoveling up their load during such travel. The buckets 19 discharge into the chute 44, and the latter 75 place such material into the buckets 35, the latter in their travel over the boom 26, delivering the material into the funnel 45. The boom 26 is positioned by the rack or pinion 29 and 30 and by the cable 41 to 80 properly position the funnel, and hence the delivery of the coal to the proper point is insured.

The device is of simple construction and is of equal facility for delivery of coal from 85 one vessel to another at sea, as for delivery of coal from a coaling wharf to a vessel, it being understood that the various parts are to be of such proportion and material as will best adapt them for the particular work 90 required.

What is claimed is:—

In a coaling device, an upright, a standard rotatably supported adjacent the upright, a charging device pivotally supported 95 on the standard, means carried by the upright and connected to the charging device to adjust the latter on the standard, a second standard rotatably mounted adjacent the upright, a delivery device pivotally mounted on said second standard, means connecting said delivery device to the upright for adjusting the delivery device on its standard, and means for transferring material from the charging device to the delivery device, said means being supported wholly by the upright and coöperating with the charging device in the full adjustment of said charging device.

In testimony whereof, I affix my signature 110 in presence of two witnesses.

OTTO BAUERLE.
